Jack L. Ford, Los Angeles, Calif.

Application December 18, 1944, Serial No. 116,993

Term of patent 14 years

(Cl. D80—9)

To all whom it may concern:

Be it known that I, Jack L. Ford, a citizen of the United States of America, residing at Los Angeles, in the county of Los Angeles and State of California, have invented a new, original, and ornamental Design for Merchandise Rack or the like, of which the following is a specification, reference being had to the drawing, forming a part thereof.

Fig. 1 is a front perspective view of a merchandise rack, showing my new design.

Fig. 2 is a cross sectional view taken on line 2—2 of Fig. 1

Fig. 3 is a sectional view taken through line 3—3 of Fig. 1.

I claim:

The ornamental design for a merchandise rack or the like, substantially as shown.

JACK L. FORD.
